(57) **CLAIM**

The ornamental design for a lid with semi-circular handle, substantially as shown and described.

DESCRIPTION

FIG. 1 is a perspective view of my design for a lid with semi-circular handle.

FIG. 2 is a perspective view of my design for the lid with a semi-circular handle.

FIG. 3 is a front view of the lid with a semi-circular handle.

FIG. 4 is a rear view of the lid with a semi-circular handle.

FIG. 5 is a right side view of the lid with a semi-circular handle.

FIG. 6 is a left side view of the lid with a semi-circular handle.

FIG. 7 is a top view looking downward on the lid with a semi-circular handle; and,

FIG. 8 is a bottom view of the lid with semi-circular handle. The surface shading and contour lines shown in the drawings represent three-dimensional character and contour of the article and are not intended to illustrate material, surface ornamentation or surface decorations.

Stippling illustrates a seal that is disposed in a circumferential groove on a lower outer portion of the lid.

The broken lines showing portions of the lid with semi-circular handle are for the purpose of illustrating environmental structure and form no part of the claimed design.
